The ornamental design for an ear plug, as shown and described.

DESCRIPTION

1. Ear plug
- 1.1 : Perspective
- 1.2 : Front
- 1.3 : Left
- 1.4 : Back
- 1.5 : Right
- 1.6 : Top
- 1.7 : Bottom
- 1.8 : Perspective

The design shows an ear plug for use in water sports, such as surfing; the ear plug has an body with an upper part and a lower part; a tip is arranged around the lower part that is adapted to be inserted into the ear canal; a membrane is arranged at the front of the upper part, which allows sound to enter the ear plug but blocks water and wind from entering the ear plug.
